(57) **CLAIM**

The ornamental design for a transmitter, as shown and described.

DESCRIPTION

FIG. 1 is a front, right and top perspective view in the used configuration with the two parts assembled together of a transmitter, showing my new design;

FIG. 2 is a front, right and top perspective view of a first component of the transmitter;

FIG. 3 is a rear, left and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and

FIG. 10 is an enlarged detail view of portion 9 encircled in FIG. 2.

FIG. 11 is a front, right and top perspective view of a second component of the transmitter, showing my new design;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof; and,

FIG. 18 is a bottom plan view thereof.

The broken lines shown in the drawings illustrate portions of the transmitter that form no part of the claimed design.

The dot-dash broken lines depict the boundaries of the enlargements that form no part of the claimed design.

1 Claim, 18 Drawing Sheets
